DESIGN FOR A BOLSTER COVER FOR PILLOWS OR SIMILAR ARTICLE

Genevieve L. Such, Chicago, Ill.

Application December 26, 1946, Serial No. 135,774

Term of patent 7 years

(Cl. D5—2)

To all whom it may concern:

Be it known that I, Genevieve L. Such, a citizen of the United States and residing in the city of Chicago, in the county of Cook, and State of Illinois, have invented a new, original, and ornamental Design for Bolster Cover for Pillows or Similar Article, of which the following is the specification, reference being had to the accompanying drawings, forming a part thereof.

On the drawings:

Fig. 1 is a perspective view of my bolster cover for pillows or similar article and looking at the openable portion thereof.

Fig. 2 is an elevational view thereof.

Fig. 3 is a rear elevational view thereof.

I claim:

The ornamental design for a bolster cover for pillows or similar article, substantially as shown.

GENEVIEVE L. SUCH.
